US0D1047220S

(12) United States Design Patent (10) Patent No.: US D1,047,220 S
(45) Date of Patent:  Oct. 15, 2024

(54) VIBRATOR FOR MASSAGE

(71) Applicant: Amoreo B.V., Haarlem (NL)

(72) Inventor: Egor Sharapkin, London (GB)

() Term: 15 Years

(21) Appl. No.: 35/517,235

(22) Filed: May 4, 2023

(80) Hague Agreement Data

Int. Filing Date: May 4, 2023

Int. Reg. No.: DM/228816

Int. Reg. Date: May 4, 2023

Int. Reg. Pub. Date: May 19, 2023

(30) Foreign Application Priority Data

Nov. 5, 2022 (EM) 015002432-0001

(51) LOC (14) Cl. 24-01
